ROTARY SLEEVE VALVE FOR INTERNAL-COMBUSTION ENGINES

Guy Davies, Kempston, England

Application June 19, 1944, Serial No. 540,935
In Great Britain August 25, 1943

4 Claims. (Cl. 123—80)

This invention relates to rotary sleeve valves for internal combustion engines of the kind wherein a cylindrical sleeve is arranged to rotate between the cylinder wall and the working piston of the engine.

According to one aspect of the invention the end of the rotary sleeve valve normally adjacent to the cylinder head is arranged to form a housing for a slidable member having at least one passage extending therethrough communicating with the combustion space of the engine and adapted to register with inlet and exhaust ports in the engine cylinder as the sleeve rotates, the slidable member being urged to engage the cylinder wall by spring means and its inner face being subjected to the pressure prevailing in the engine cylinder. According to another aspect of the invention the end of the sleeve valve normally adjacent to the cylinder head has a cavity forming a housing for a slidable member having at least one passage extending therethrough communicating with the combustion space of the engine and adapted to register with the inlet and exhaust ports in the engine cylinder as the sleeve rotates, the outer face of the slidable member being adapted to engage the cylinder wall and the inner face being subjected to the pressure prevailing in the engine cylinder.

To enable the invention to be fully understood it will now be described with reference to the accompanying drawings, in which:

Fig. 1 is a sectional elevation of an engine cylinder with a rotary sleeve valve according to one embodiment of the invention,

Fig. 2 is a side elevation of the cylinder, part of the wall being broken away to expose the slidable member in the rotary sleeve,

Fig. 3 is a section on line 3—3 of Fig. 2.

Figure 4 is a vertical section taken on a different section line from Figure 1 and shows the valve 5 opposite a blank portion of the cylinder and not opposite the port 9, this Figure 4 also showing the connecting rod and crankshaft.

As shown in the accompanying drawings a cylindrical sleeve 1 is arranged between the piston 2 and cylinder 3 of an internal combustion engine. The piston 2 has a connecting rod 2a connected with the crankshaft a. The end of the sleeve adjacent to the cylinder head comprises a solid portion 4 which is recessed to form a housing for a substantially cylindrical slid- able piston like member 5 which is urged into engagement with the inner wall of the cylinder 3 by springs 6 which are arranged in pockets 7 in the solid portion 4 of the sleeve. The mem-

ber 5 is formed with a passage 8 extending therethrough of W section and the cylinder 3 is formed with inlet and outlet ports 9, 10 of similar section connected respectively with conduits not shewn for supplying a combustible mixture and exhausting the burnt gases. A screw-threaded sparking plug aperture 11 is also provided. Piston rings 12 are arranged in the member 5 to ensure a gas-tight fit.

The sleeve 1 has a stem 32 carrying a gear wheel 33 meshing with a gear wheel 34 on a tower shaft 35. A bevel pinion 36 is mounted on the lower end of the shaft 35, and is rotated by a bevel pinion 37 on the crankshaft a. When the valve 1 is rotated by this gearing, the slid- able member 5 is moved over wall 3 and regis- 10ters in turn with the inlet port, sparking plug or injector and exhaust port 10 in timed sequence to the stroke of the piston 2. It will be under- 15stood that instead of being of W section the inlet and exhaust passages may be of any other convenient shape in cross section. Instead of the member 5 sliding in a path substantially at right angles to the axis of the sleeve 1, it may be mounted at an angle to the said axis.

According to the present invention the sleeve and slidable member have a purely rotary motion imparted to them, and further the slidable member is urged by a spring into engagement with the cylinder and has its inner face exposed to the pressure prevailing in the cylinder, whereby it is forced against the cylinder by gas pressure on the compression and power strokes of the piston.

The portion 4 of the sleeve housing the slidable member 5 may have chamber 38 adapted to be supplied with oil for cooling purposes.

I claim:

1. A rotary sleeve valve of the kind referred to wherein the end of the sleeve normally adjacent to the cylinder head is arranged to form a housing for a slidable member having at least one passage extending therethrough communicating with the combustion space of the engine and adapted to register with inlet and exhaust ports in the engine cylinder as the sleeve rotates, the slidable member being urged to engage the cylinder wall by spring means and its inner face being subjected to the pressure prevailing in the engine cylinder.

2. A rotary sleeve valve according to claim 1 wherein the sleeve comprises a cylindrical portion arranged between the piston and cylinder and a solid portion having a recess to house the slidable member.

3. A rotary sleeve valve of the kind referred to wherein the end of the sleeve normally adjacent to the cylinder head has a cavity forming a housing for a slidable member having at least one passage extending therethrough communicating with the combustion space of the engine and adapted to register with the inlet and exhaust ports in the engine cylinder as the sleeve rotates, the outer face of the slidable member being adapted to engage the cylinder wall and the inner face being subjected to the pressure prevailing in the engine cylinder.

4. A rotary sleeve valve of the kind referred to wherein the end of the sleeve normally adja-

cent to the cylinder head has a cavity forming a housing for a substantially cylindrical piston-like member slidable in a path substantially at right angles to the axis of the sleeve, and having at least one passage extending therethrough communicating with the combustion space of the engine and adapted to register with inlet and exhaust ports in the engine cylinder as the sleeve rotates, the outer face of the piston-like member being adapted to engage the cylinder wall and the inner face being subjected to the pressure prevailing in the engine cylinder.

GUY DAVIES.
